UNITED STATES PATENT OFFICE.

GEORGE G. ROSS, HARRY E. ROSS, AND LEO D. ROSS, OF GREENSBURG, PENNSYLVANIA.

AUTOMATIC TRAIN-PIPE COUPLING.

1,168,677.

Specification of Letters Patent. Patented Jan. 18, 1916.

Application filed March 8, 1915. Serial No. 12,833.

To all whom it may concern:

Be it known that we, GEORGE G. ROSS, HARRY E. ROSS, and LEO D. ROSS, citizens of the United States of America, residing at 5 Greensburg, in the county of Westmoreland and State of Pennsylvania, have invented certain new and useful Improvements in Automatic Train-Pipe Couplings, of which the following is a specification, reference being had therein to the accompanying drawing.

This invention relates to automatic train pipe couplings of an impact type, and has for its object to provide an automatic train 15 pipe coupling of such type, in a manner as hereinafter set forth, with an automatic train pipe coupling head and auxiliary attachments operated by the coupling of railroad cars or vehicles.

20 A further object of the invention is to provide an automatic train pipe coupling of an impact type provided with means, in a manner as hereinafter set forth, operated by the movement of railroad cars or vehicles, for imparting an oblique movement to 25 an automatic train pipe coupling head.

A further object of the invention is to provide an automatic train pipe coupling of an impact type with means, in a manner 30 as hereinafter set forth, operated by the movement of railroad cars or vehicles, for transmitting a reciprocating motion, to be imparted to an automatic train pipe coupling head.

35 Further objects of the invention are to provide an automatic train pipe coupling which is comparatively simple in its construction and arrangement, strong, durable, efficient and convenient in its use, readily attached to a car and comparatively inexpensive to manufacture and maintain.

With the foregoing and other objects in view, the invention consists of the novel construction, combination and arrangement of 45 parts as hereinafter more specifically described and illustrated in the accompanying drawings, wherein is shown an embodiment of the invention, but it is to be understood that changes, variations and modifications 50 can be resorted to which come within the scope of the claims hereunto appended.

In the drawings, wherein like reference characters denote corresponding parts throughout the several views:—Figure 1 is 55 an exterior view of the automatic train pipe couplings, Fig. 2 is a sectional detail of an

automatic train pipe coupling, Fig. 3 is a perspective view of an automatic train pipe coupling head, Fig. 4 is a view of an automatic train pipe coupling head equipped with a conduit hose and standard train pipe coupling. Fig. 5 is a view of automatic train pipe coupling heads locked in conjunction. Fig. 6 is a horizontal sectional view of the automatic coupling head. 65

Referring to the drawings in detail, A denotes the automatic train pipe coupling head provided with the beveled tongue A¹ and the flared guiding hood A², the purpose of which will be presently referred to. 70 The inner surface of the beveled tongue A¹ provides the coupling face A³ said face having seated therein the gasket V, a longitudinal air passage V¹ extends throughout the length of the device. 75

The reference character B¹ denotes a hollow ball terminating in a tubular neck and contained in the casing B, said tubular neck being attached to the automatic coupling head A, fitted in the casing B and seated 80 on the hollow ball B¹ is the socket B³ said socket having therethrough a circular passage V¹, extending into the casing and seated on the socket B³ is the bushing B² having a circular passage therethrough and 85 screw threads on each end, a projection K is inserted in the ball B¹ and extends through an opening in the casing B preventing the ball B¹ from revolving in said casing beyond a desired point. 90

Attached to the bushing B² by means of screw thread is the female tubular member D, having extending portion F as may readily be seen said extending portion may be of any desired shape but in this instance it 95 is of a circular form, extending into the female tubular member D is the male tubular member C having the extending portion F¹ similar to the extending portion F on the female tubular member D, the male tubular 100 member C is provided with a suitable packing ring P, surrounding the tubular members D and C, between extending portions F and F¹ is the spring E maintaining said tubular members D and C in an extended 105 position until force is applied to the automatic coupling head A greater than the tension of said spring, extending through openings provided in the projecting portions F and F¹ of the tubular members D 110 and C are the tie bolts Y, said tie bolts being held stationary in one of the said pro-

jecting portions and being free to move in the other one, this arrangement providing a means to limit the extension of said tubular members.

- 5 A means is provided as shown on Fig. 4 of the drawings, of connecting a car equipped with the present standard of train pipe couplings with the automatic train pipe coupling described in the specifications and 10 shown on the drawings of the present invention, this object is accomplished by equipping an automatic train pipe coupling head, of the character shown on the drawings with the lock screw W and a standard 15 hose and coupling X, the attachment described above may be used when it is required.

Generally describing said automatic train pipe coupling, the same consists of an automatic coupling head A having a face A³ capable of mating at an angle with face of a duplicate automatic coupling head, on opposite car or vehicle, a flared guiding hood A² extending forward, at an angle on three 25 sides, on the top and bottom sides said flared guiding hood overlapping the automatic train pipe coupling head A half way, and returning in an angular direction to a point A⁵ near the corner of the flared guiding 30 hood A², on the face side the flared guiding hood A² extending across the automatic coupling head A and extending forward and flaring outwardly from the face A³, forming with the top and bottom portions of said 35 flared guiding hood the socket A⁴, said socket being adapted to receive the point of a beveled tongue A¹ of a mating automatic train pipe coupling head, the flare of said guiding hood A² being adapted for 40 the purpose of guiding the beveled tongue A¹ of a mating automatic train pipe coupling head, on opposite car or vehicle into the socket A⁴, a gasket V seated in the face A³ of the beveled tongue A¹, said gasket 45 being adapted to mate with a similar gasket in a mating automatic train pipe coupling head.

When the beveled tongue A¹ is forced into the socket A⁴ a pair of automatic train pipe 50 coupling heads, of the character described will be locked in conjunction.

As may readily be seen by reference to the drawings, when several cars or vehicles in a railroad train are in a curvated position the arrangement shown at B, B¹, B² and B³ will assist the automatic train pipe coupling heads A to assume an oblique position in regard to the longitudinal position of the car bodies.

60 When the several cars and vehicles are coupled together in a railroad train, the arrangement of the tubular members, spring and tie bolts as shown at, D and C, E and Y, respectively, will permit a reciprocating motion to be imparted to an automatic 65

train pipe coupling head of this character, when a railroad train consisting of cars and vehicles is in motion.

It is intended that the mechanism described and shown on the drawings is to be 70 attached to the underside of a car body by means of pipe hangers of a convenient size and shape.

Having now fully described our invention in automatic train pipe couplings, what 75 we claim as new and novel and desire to secure by Letters Patent of the United States of America is:—

1. An interlocking automatic train pipe coupling head of the impact type comprising, in combination, an automatic coupling head, an oblique movable conduit joint, a parallel shiftable conduit joint, said automatic coupling head having an annular passage there-through, a flared guiding hood 80 extending in an angular direction from said automatic coupling head, capable of guiding a beveled tongue of adjunctive automatic coupling head into a socket, a beveled tongue capable of engaging a flared guiding hood of an adjunctive automatic 85 coupling head, an automatic train pipe coupling head capable of interpenetration with an adjunctive automatic train pipe coupling head, an automatic coupling head capable of 90 slidable engagement with an adjunctive automatic coupling head. 95

2. An interlocking automatic train pipe coupling head of the impact type comprising, in combination, an adjunctive automatic coupling head, an oblique movable conduit joint, a parallel movable conduit joint, said automatic coupling head having an annular passage there-through, flared guiding hood 100 extending in an angular direction from said automatic coupling head, capable of guiding a beveled tongue of adjunctive automatic coupling head into a socket, a beveled tongue capable of engaging a flared guiding hood of an adjunctive automatic coupling head, an automatic train pipe coupling head capable of 105 interpenetration with an adjunctive automatic coupling head, an automatic coupling head capable of slidable engagement with an adjunctive 110 automatic coupling head. 115

3. An interlocking automatic train pipe coupling head of the impact type comprising, in combination, an automatic coupling head, an oblique movable conduit joint, a parallel shiftable conduit joint, said automatic coupling head having an annular passage there-through, a flared guiding hood 120 extending in an angular direction from said automatic coupling head, capable of guiding a beveled tongue of an adjunctive auto- 125

130

matic coupling head into a socket, a beveled tongue capable of engaging a flared guiding hood of an adjunctive automatic coupling head, an automatic train pipe coupling head
5 capable of interpenetration with an adjunctive automatic train pipe coupling head, an automatic coupling head capable of slidable engagement with an adjunctive automatic coupling head, an automatic train pipe coupling of the character described and means
10 for permitting to an automatic train pipe coupling head a reciprocating motion.
4. An interlocking automatic train pipe coupling of the impact type, an automatic coupling head, said automatic coupling head having an annular passage there-through, a flared guiding hood extending in an angular direction from said automatic coupling head, capable of guiding a beveled tongue
15 of an adjunctive automatic coupling head
20

into a socket, a beveled tongue capable of engaging a flared guiding hood of an adjunctive automatic coupling head, an automatic train pipe coupling head capable of interpenetration with an adjunctive automatic train pipe coupling head, an automatic coupling head capable of slidable engagement with an adjunctive automatic coupling head, an interlocking automatic train pipe coupling head of the character described and means provided for making connection with fluid conduit lines provided with standard hand couplings to the automatic coupling head described.
